UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

Application filed January 3, 1922. Serial No. 526,565.

To all whom it may concern:

Be it known that I, BENJAMIN E. GETCHELL, a citizen of the United States of America, residing at Plainville, Connecticut, have invented a new and useful Electric Switch, of which the following is a specification.

My invention relates to an electric switch.

It is an object of the invention to provide novel means for holding a switch in closed circuit position until the opening movement is initiated.

It is a further object to provide novel means for opening a switch with a snap action after the opening movement has been initiated.

My invention in its preferred form includes a switch having fixed and movable contacts. The operating means for the one or more movable contacts is of any suitable form. A latch bar is positioned so as to contact with the switch operating means and a spring serves to constantly urge the latch bar in one direction, and the latch bar coacting with the switch operating means serves to hold the switch in closed circuit position until the opening movement of the switch is initiated, after which the latch bar urged by the spring, opens the switch with a snap action.

I have disclosed an illustrative form of my invention in connection with a commercial type of motor starting switch.

In the drawings:

Fig. 1 is a perspective view of a motor starting switch and illustrating parts of my invention.

Fig. 2 is a fragmentary partially diagrammatic sectional view illustrating the invention and showing the switch and associated parts in open circuit position.

Fig. 3 is a view similar to Fig. 2, but taken at right angles to Fig. 2.

Fig. 4 is a view similar to Fig. 2 but showing the switch parts in closed circuit position.

In said drawings, 5 indicates any suitable or desired type of switch box. 6—6 indicate two of a plurality of movable contacts which in the form shown are the usual type of pivoted switch blades. 7—7 designate fixed contacts for the blades when the latter are in motor starting position. 8—8 designate the fixed contacts for the blades when the switch is in motor running position.

In the form disclosed, the movable contacts are actuated by means of a pivoted crank 9 operable in the box. An external handle 10 is connected to the crank 9 in order to permit operation of the switch from the outside of the box. A lost motion connection 11 may be provided between the movable contacts and the operating crank as for instance as shown in Sutherland Patent No. 1,271,520.

The connection between the operating handle and the operating crank within the box is preferably such that the handle may be moved to position the blades 6 in the motor starting position indicated in Fig. 1, and before the switch may be moved to motor running position the handle must be moved backward slightly, after which the crank may then be actuated to move the switch blades 6 into contact with the fixed contacts 8. This latter position of the switch is the running position. The connection above described may be of the type disclosed in the patents to Ahlstrom #1,231,229, or Knudsen #1,364,384, to either or both of which patents reference is hereby made for a fuller disclosure.

Novel means are provided for holding the switch in closed circuit position until the opening movement is initiated, after which the switch is thrown to open circuit position with a snap action. In the illustrative embodiment of my invention shown in the drawings, a latch bar 15 is pivoted to some part, preferably the side of the box 5. In the form disclosed the latch bar has a slot 16 therein provided with an opening 17 to permit easy insertion and removal of the operating crank 9. A spring 18 is connected to the latch bar to urge the latter in one direction. In one end of the slot 16 there may be formed a holding shoulder or latch 19 which cooperates with the operating crank 9 to hold the latter and consequently the switch blades in closed circuit position.

When the blades are in this closed circuit position, the latch bar and shoulder 19 urged by the stressed spring, serves to clutch or bind the operating crank 9 and thus effectively prevents the accidental opening of the switch. It will be seen that when the handle is moved in a direction to open the switch, the part of the operating crank 9 engaged by the shoulder 19, will move and be disengaged

from the holding shoulder. During this slight movement to disengage the crank and shoulder, the spring will be further stressed. As soon as the crank is disengaged from the shoulder, a surface 20 of the latch bar will act on the crank 9 and the spring in drawing the latch downwardly, as viewed in the drawings, will cause the operating crank to be moved to open the switch with a snap 10 action.

The operation is as follows: Assuming the parts to be in the position partially diagrammatically illustrated in Fig. 2, the handle 10 is moved to cause the switch blades 6 to engage the fixed contacts 7. If the connection between the handle and operating crank is such as is disclosed in the patents above referred to, the handle may not be further moved in the closing direction with 15 out first moving the handle back slightly. The position of the parts in Fig. 1 is the motor starting position in which the fuses shown therein are not in circuit. If now the handle be moved back slightly, the handle 20 may be again moved in the closing direction to cause the switch blade 6 to engage the contacts 8. The fuses will then be in circuit and the switch in the motor running position. The position of the operating 25 crank and the latch bar in the motor running position is disclosed in Fig. 4.

It will be clear that during the movement of the crank 9 from the open circuit position shown in Fig. 2 to the closed circuit 30 position shown in Fig. 4, the crank will slide along the surface 20 and in raising the latch bar the spring 18 will be stressed. When the crank is engaged behind the shoulder 19 the switch blades and crank will 35 be firmly held in the closed circuit position until the opening movement of the crank is initiated.

When it is desired to open the switch, the handle 10 is drawn back so as to cause the 40 operating crank 9 to be disengaged from the shoulder 19, after which the surface 20 of the bar will act under the influence of the spring 18 so as to open the switch with a snap action.

50 In the construction shown, the same spring which moves the switch also cooperates with the latching means to securely hold the switch in the on position.

While I have disclosed a preferred embodiment of my invention, and have shown the same in connection with a commercial type of enclosed motor starting switch, I wish it understood that various changes may be made within the scope of the appended 55 claims and that the invention may be used in connection with other types of switches.

I claim:

1. In an electric switch, fixed and movable contacts, means for moving said movable contact, a pivoted latch bar coacting

with said means, a spring at all times urging said latch bar in the same direction to hold the movable contact in closed circuit position until the opening movement of the movable contact is initiated, and to then move 70 the movable contact to open circuit position with a snap action.

2. In an enclosed switch, a switch box, fixed and movable contacts in said box, an operating crank journaled in said box for 75 moving said movable contacts, a latch bar pivoted in said box and coacting with said operating crank to hold the switch contacts in closed position, a spring at all times urging said latch in the same direction, said 80 latch having a surface coacting with said operating crank for moving the movable contacts to open circuit position after the opening movement has been initiated.

3. In an electric switch, fixed and movable contacts, means for moving the movable contact, a latch bar coacting with said means, a spring at all times urging said latch bar in the same direction, said latch bar having a holding shoulder coacting with 90 said switch operating means for holding the movable contacts in closed circuit position, and said latch bar having a surface coacting with the switch actuating means for moving the movable contact to open circuit 95 position with a snap action after the opening movement has been initiated.

4. In an electric switch, a movable switch blade and fixed contact, blade operating means for moving the blade, a pivoted latch 100 bar having a holding shoulder and a cam surface thereon, a spring at all times urging said latch bar in the same direction, said holding shoulder serving to hold said blade operating means in position to hold 105 the switch blade in closed circuit position until the opening movement of the blade actuating means is initiated, said cam surface thereafter serving to move the blade to open circuit position with a snap action. 110

5. In an electric switch, fixed and movable contacts, an operating crank for moving said movable contact, a pivoted latch bar having a cam surface engaging the operating crank, a spring at all times urging said latch bar 115 in the same direction, said latch bar serving to hold the operating crank in the closed circuit position until the opening movement of the switch is initiated, after which said cam surface throws the crank to open circuit 120 position with a snap action.

6. In an electric switch, fixed and movable contacts, an operating crank for said movable contact, a pivoted latch bar having an open sided slot therein, said latch bar having a holding shoulder at one end of the slot, a spring at all times urging said latch bar in the same direction, said operating crank being normally positioned in said slot, said shoulder serving to hold the oper- 125

ating crank in one position until the opening movement of the switch is initiated.

7. In an electric switch, fixed and movable contacts, an operating crank for said movable contact, a pivoted latch bar having a slot therein, said latch bar having a holding shoulder at one end of the slot and a hook portion at the other end of the slot, said operating crank extending through said slot, 10 and a spring for said latch to hold said shoulder in engagement with the crank and maintain the latter at one end of its path of movement until disengaged from said shoulder and thereafter to move said crank 15 towards the other end of said path.
8. In an electric switch, fixed and movable contacts, an operating crank for said movable contact, a pivoted latch bar having a slot therein, said latch bar having a holding 20 shoulder at one end of the slot and a hook portion at the other end of the slot, said operating crank extending through said slot, and a spring for said latch to hold said shoulder in engagement with the crank and 25 maintain the latter at one end of its path of movement until disengaged from said shoulder and thereafter to move said crank towards the other end of said path, said hook portion engaging the crank to limit 30 said latter movement.

9. In an electric switch, a number of fixed contacts, a post, a movable contact pivoted thereto and adapted to cooperate with one or more of said fixed contacts, a crank to operate said movable contact, a pivoted latch bar having a slot through which said crank extends, said slot having a notch providing a shoulder to engage said crank when the switch is closed, and a spring fastened to said latch bar and to a point outside the zone 40 between the post and any fixed contact, said spring actuating the latch bar to hold the switch in closed circuit position until the crank is moved beyond said shoulder and thereafter opening the switch with a snap 45 action.

10. In an electric switch, a movable switch blade and fixed contact, means for moving the blade, a pivoted latch bar having a holding shoulder and a cam surface thereon, and 50 a spring to actuate said latch bar, said holding shoulder and spring serving to hold the blade in closed circuit position until opening movement of the blade is initiated, and said cam surface thereafter serving to 55 move the blade to open circuit position with a snap action and to limit the extent of opening movement of the blade.

BENJAMIN E. GETCHELL.
